UNITED STATES PATENT OFFICE.

TULLIO V. GIARA, OF NEW YORK, N. Y.

DIPLEX TYPE-WRITING TELEGRAPH.

1,200,186.

Specification of Letters Patent. Patented Oct. 3, 1916.

Application filed March 9, 1911, Serial No. 613,462. Renewed February 26, 1916. Serial No. 80,760.

To all whom it may concern:

Be it known that I, TULLIO VENIER GIARA, a subject of the King of Italy, and a resident of the city of New York, in the county and State of New York, have invented certain new and useful Improvements in Dplex Type-Writing Telegraphs, of which the following is a full, clear, and exact description, reference being had to the accompanying drawings, forming part of this specification.

This invention relates to the transmission of intelligence to a number of points, and has for its object to provide certain mechanical details in the construction of typewriters and other machines operated in a similar manner, and electrical connections whereby the writing on one machine is repeated on the other or others, and vice versa.

A further object of this invention is to provide electromagnetic means and connections of a simple character adapted to be applied to any typewriter for the purpose of receiving and sending electrical impulses for operating or by operating the keys of said typewriter; and a still further object is to provide an improved construction of type levers whereby a machine in the circuit can both receive and send messages, without materially changing its construction, and without impairing its usefulness as a common typewriter.

With these and other objects in view, as will more fully appear as the description proceeds, my invention consists in certain constructions and arrangements of parts as will be disclosed and claimed in the appended claims.

Referring to the drawings, Figure 1 shows a way of arranging the circuit between two corresponding keys of two typewriters, each machine having a source of current supply; Fig. 2 shows a way of connecting several machines with a central battery, so that each machine can transmit to or receive messages from all the others; Fig. 3 illustrates how the connection between two machines can be obtained by means of a switchboard and an operator in attendance; Fig. 4 shows a method of connecting two machines, whereby upon the sending of a message from one machine, the other is automatically set in the receiving position; Fig. 5 illustrates a way of sending messages by means of an auxiliary keyboard, without altering the keyboard on the typewriter; and Fig. 6 shows a way of modifying the circuit with

the introduction of artificial lines, when the resistance of the line should be considerable.

The figures show only diagrammatically my improved ways of making the connections, for the purposes above specified; it being understood that said connections, shown only for one key, are repeated in each and every key of the machines, the different wires being formed into cables for convenience in putting up the line.

Referring to Fig. 1, 1, 2, 1', 2', are the keys of the connecting typewriters, modified so that the key 1, 1', is independent from the lever 2, 2'. The pressing of the key 1, 1', will cause the lowering of lever 2, 2', but said lever 2, 2', may be attracted by an electro-magnet to print the letter, without disturbing the key 1, 1'. Under the lever 2, 2' of each key, is provided an electro-magnet 3, 3', the armature of which 4, 4', is attached to the lever 2, 2'; the coil of said electro-magnet is attached at one end to the line L at 5, 5', and at the other end to the ground or return wire R at 6, 6'. Under the key 1, 1', is a contact 7, 7', which is normally kept open by means of a spring 8, 8', or by any other suitable means, but which can be closed by pressing the key 1, 1'. Said contact 7, 7', is connected on one side with the line L at 5, 5', and on the other with a source of electricity 9, 9', through the circuit 10, 10'.

11, 11', 12, 12', are switches provided for the purpose of detaching the machines from the circuit, but are normally closed. Pressing key 1, contact 7 is closed; the two closed circuits 7-5-3-6-9-10-7 and 7-5-L-5'-3'-6'-R-6-9-10-7 are formed, and the electro-magnets 3, 3', being energized, will attract the levers 2, 2', and cause the printing of the corresponding letters. Pressing key 1', similar circuits will be produced, with similar results. The source of electricity 9, and the ground or return wire R, can be the same for all the keys, or a number of machines.

The separation of the type lever from the contact key, as hereinbefore described, is an absolute necessity in devices of this character; in fact, if parts 1, 1' should be connected to parts 2, 2', and one contact should be closed in the circuit, all the armatures would be attracted by the corresponding electro-magnets, against the action of springs 8, 8'. If these be weaker than the pulling action of the electro-magnets, the levers would not return to their original positions; while if

springs 8, 8' should be stronger, the action of the electromagnets would not be sufficient to operate the levers. In the various dispositions shown, springs 8, 8', only need to pull back keys 1, 1', thus breaking the contact at 7, 7', when the electro-magnets will automatically release armatures 4, 4', on levers 2, 2'.

I am aware that typewriters and similar machines have been electrically connected, the levers being operated by means of electro-magnet controlled by a separate keyboard; but I do not know of any device in which the connections are so made as to cause the simultaneous operation of the various machines in the circuit; nor do I know of any device of this character having a keyboard which can be used both for writing in the ordinary manner, and for transmitting messages to other machines. All the movements that a typewriter can make, such as the spacing of the lines, the return of the carriage, etc., can be produced in a similar manner; and the connections as described here, can be made not only between typewriters, but between any other machines of like character, where it is desired to make one of said machines repeat automatically the movements of the other, and vice versa. Moreover, said connections are not limited to only two machines, but can be extended to any number of machines in the circuit in such a way that the writing on one of them is repeated by all the others. Such a disposition is illustrated in Fig. 2, in which a number of machines is worked from a central battery 13.

The machines are modified as described above, the keys being composed of a key 14, 14', 14'', 14''', independent from the lever 15, 15', 15'', 15''', and an electro-magnet 16, 16', 16'', 16''', being provided underneath said levers in a position where it will be able to attract the same. The coil of each electro-magnet is connected at one end to the line, at 17, 17', 17'', 17''', and at the other end to the return wire or ground, R', at 18, 18', 18'', 18'''. The line 19, 19', 19'', 19''' from the central battery 13, feeds the electric current to each machine, through the normally open contacts 20, 20', 20'', 20''', underneath the keys 14, said contacts being kept open by means of a spring or other suitable means 21, 21', 21'', 21'''. 22, 22', 22'', 22''', are switches on the sending circuit of each machine, and 23, 23', 23'', 23''', are switches on the receiving circuit, said switches being normally closed. In this position, each of the machines in the circuit can send and receive messages from all the others; when it is desired to communicate only between two of the machines, the switches 23 of the others are opened, putting the machines out of receiving. When it is desired to use one machine independently

from all the others, the opening of the corresponding switches 22 and 23, will detach said machine entirely from the circuit. It is obvious that the position of the switches in the circuit can be changed, and that means 70 can be provided in each machine to vary the resistance of the different circuits.

The connection between the machines can be obtained by means of a switchboard, as shown in Fig. 3; the wire of each machine, 75 coming to a special jack on the board, and a local connection ending in two plugs P, P', connecting the machines wanted. The local connection can have in shunt a machine O, with which the operator at the board can 80 receive the call and make the desired connections.

Fig. 4 illustrates a circuit in which each key of the typewriter has a switch commanded by electro-magnets R and T. This 85 switch can connect the line L'', either with electromagnet E at D or with the key K at F, so as to put the machine in the receiving or in the transmitting position.

Electro-magnets R and T are connected 90 to electro-magnets T', R', on the corresponding machine in such a way that when key M is pressed, R and T' are energized; R attracts switch S, and T' attracts switch S', so that one of the machines is put on 95 the sending position, while the other goes on the transmitting position. The reverse happens in pressing either of the keys N, N'. Switches S, S', are multiple, and can make at the same time all the contacts corresponding to the entire keyboard of the machine. Sometimes it is preferable to have a separate keyboard at a distance from the typewriter; this avoids the necessity of dividing the typewriter levers in two parts, 105 and moreover, does not require the opening of a switch when it is necessary to use the typewriter without sending messages. Such a disposition is clearly illustrated in Fig. 5, 100 where an auxiliary keyboard 24, 24', is connected to each machine.

Fig. 6 shows a disposition used when the resistance of the line is considerable, and it is necessary to balance it by introducing an artificial line in the circuit. This 115 is modified in such a way that the return wire 25 is normally connected to the receiving electro-magnet 26, 26', by way of contact 27, 27', normally closed; but on pressing one of the keys 28, 28', the corresponding contact 27, 27', is opened, and the circuit of the electro-magnet is closed by way of the corresponding resistance 29 or 29'.

From the foregoing it will be seen that in my improved arrangement the electro-magnets of corresponding keys of the various machines in the line are permanently connected in parallel with the line, and are provided with independent switches for their connection or disconnection, when de- 125 13

sired; so that each impulse sent in the line by closing one of the contacts, is sent through all the magnet coils connected, the various machines in the circuit being thus 5 simultaneously operated together with the sending machine. It will also be seen that I provide an improved construction of type-levers whereby a single keyboard can be used to operate a machine mechanically or 10 electrically, at the same time operating the other machines in electrical connection therewith.

The invention covered by the foregoing description, and by the appended claims, 15 may be varied in its various details without substantially departing from its fundamental idea; and I reserve myself the right of bringing to the same all those changes and modifications which enter fairly into 20 the scope of the following claims.

Having thus described my invention, what I claim as new, and desire to secure by Letters Patent of the United States, is:

1. In a device of the character described, 25 the combination of a machine comprising a plurality of operating levers, a plurality of electromagnets arranged to control said levers individually, an electric source of supply connected to said electromagnets, keys adapted to mechanically control said levers and adapted to remain stationary when said levers are independently operated, and switches controlling said electromagnets and operated by said keys; for the purposes 35 as set forth.

2. In a device of the character described 40 the combination of a machine comprising a plurality of operating levers, a plurality of electromagnets arranged to control said levers individually, an electric source of supply, keys also adapted to mechanically control said levers, and connections between said electric source of supply and said electromagnets whereby upon said keys being 45 mechanically operated said electromagnets will be energized and will actuate the corresponding levers, and upon said electromagnets being independently energized the corresponding levers will be actuated independently 50 of the corresponding keys; for the purposes as set forth.

3. In a device of the character described, 55 the combination of a machine comprising a plurality of operating levers, a plurality of electromagnets arranged to control said levers individually, each electromagnet having its armature connected to the lever controlled thereby, an electric source of supply connected to said electromagnets, keys detached from said levers and adapted to mechanically control the same, and switches operated by said keys and controlling said electromagnets; substantially as set forth.

4. In a device of the character described, 60 65 the combination of a machine comprising a

plurality of operating levers, an electric source of supply, a plurality of electromagnets each controlling a lever, electrical connections between said electromagnets and said electric source of supply, normally 70 open switches for closing or opening said connections, a key for each lever detached from the same and adapted to operate such mechanically and at the same time to close the switch of the corresponding electromagnet, and means for automatically returning 75 said switches to their original position.

5. In a device of the character described, 80 the combination of a writing machine having a plurality of operating levers, electromagnets controlling said levers in circuit with an electric source of supply, normally open switches in the electromagnet circuits, keys adapted to operate said levers either mechanically or by closing said switches to 85 actuate the electromagnets, and means other than said switches for effecting operation of said levers by said electromagnets, said keys being arranged to remain idle during 90 such latter operation.

6. In a typewriting telegraph, and in combination with a number of machines each comprising a plurality of operating levers, electromagnets controlling said levers, and an electric source of supply, a plurality 95 of line circuits each connecting in parallel all the electromagnets controlling corresponding levers on the various machines both when sending and when receiving; for the purposes as set forth.

7. In a typewriting telegraph, and in combination with a number of machines each comprising a plurality of operating levers, an electric source of supply, electromagnets individually controlling said levers, line circuits connecting in parallel electromagnets operating corresponding levers on the various machines both when sending and when receiving, and key-boards having keys corresponding to each circuit 100 adapted to close the same, thereby causing the energization of all the electromagnets connected thereto, and the simultaneous operation of the corresponding levers.

8. In a typewriting telegraph, and in 115 combination with a number of machines each comprising a plurality of operating levers, and with an electric source of supply, electromagnets individually controlling said levers, line circuits connecting in parallel all 120 the electromagnets operating corresponding levers on the various machines both when sending and when receiving, normally open connections between said circuits and said electric source of supply, and keyboards controlling said connections; substantially as 125 set forth.

9. The combination of a number of machines each comprising a plurality of operating levers, an electric source of supply, 130

- electromagnets individually controlling said levers, line circuits connecting in parallel all the electromagnets controlling corresponding levers on the various machines both 5 when sending and when receiving, connections between said circuits and said electric source of supply, normally open switches inserted in said connections, keyboards having keys for closing said switches, and 10 means for automatically returning said switches to their original position.
10. The combination of a number of machines each comprising a plurality of operating levers, an electric source of supply, 15 electromagnets individually controlling said levers, line circuits common to electromagnets corresponding to levers of the same denomination on the various machines, secondary circuits connecting in parallel 20 said electromagnets to said line circuits both when sending and when receiving, means for disconnecting each secondary circuit from its line circuit, connections between said line circuits and said electric source of 25 supply, normally open switches inserted in said connections, key-boards having keys for closing said switches, and means for automatically returning said switches to their original position.
20. 11. The combination of a number of machines each comprising a plurality of operating levers, an electric source of supply, electromagnets individually controlling said levers, line circuits connecting in parallel

electromagnets controlling corresponding 35 levers on the various machines, connections between said circuits and said electric source of supply, normally open switches inserted in said connections, a key-board on each machine having a key for each operating 40 lever adapted to mechanically control the same and to remain stationary when said levers are independently operated by said electromagnets, said keys closing said switches upon being depressed by the operator, and means for automatically returning 45 said switches to their original position.

12. The combination of a number of machines each comprising a plurality of operating levers, an electric source of supply, 50 electromagnets individually controlling said levers, line circuits connecting in parallel electromagnets controlling corresponding levers on the various machines, connections between said circuits and said electric 55 source of supply, normally open switches inserted in said connections, a key-board on each machine having a key for each operating lever detached from the same, adapted to operate said levers mechanically and to 60 close the corresponding switches, and means for returning said switches to their original position.
